(57) **CLAIM**

The ornamental design for a wheel chock, as shown and described.

DESCRIPTION

FIG. 1 is a front and left side perspective view of a wheel chock showing our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a rear and right side perspective view thereof.

The broken lines in the drawings illustrate portions of the wheel chock that form no part of the claimed design.

1 Claim, 5 Drawing Sheets
